P. J. SHOMER *INVENTOR.*

BY Richey, Slough + Watts

HIS ATTORNEY'S

UNITED STATES PATENT OFFICE.

PETER J. SHOMER, OF CLEVELAND, OHIO.

DEVICE FOR ABATING SMOKE.

Application filed May 9, 1923. Serial No. 637,683.

To all whom it may concern:

Be it known that I, PETER J. SHOMER, a citizen of the United States, and a resident of Cleveland, county of Cuyahoga, State of Ohio, have invented certain new and useful Improvements in a Device for Abating Smoke, of which the following is a specification.

This invention relates to a device for abating smoke in furnaces and which also assists in promoting complete combustion of the fuel therein.

An object of my invention is to provide a device which is associated with a furnace to hold the combustible materials thereunder in close proximity to the fire, whereby they will be completely burned, thus abating the smoke which is caused when such materials are permitted to pass from the chimney.

Another object of my invention resides in a device for providing and maintaining an air blanket, which extends downwardly across the firebox from opposite sides of the furnace thereby holding the combustible material thereunder, in close proximity to the fire, until completely burned.

Another object of my invention resides in the process I employ for abating smoke, which consists of directing an oxygen containing gas into the firebox in such a manner as to retain the combustible material completely thereunder.

Another object of my invention resides in a device, associated with a furnace, whereby air is fed from disaligned outlets at opposite sides of the firebox to provide an air blanket across the firebox retaining the combustible fuel materials thereunder in close proximity to the fire until completely burned.

These and other objects will appear in the following specification and claim.

In the drawings, Fig. 1 is a longitudinal section through the furnace taken on line 1—1 of Fig. 3 showing my invention and its relation at one side of the furnace;

Fig. 2 is a transverse section taken on line 2—2 of Fig. 3 showing my device at opposite sides of the furnace;

Fig. 3 is a section taken on line 3—3 of Fig. 1 showing a top plane view of my device positioned within the furnace;

Fig. 4 is a view taken on line 4—4 of Fig. 1 illustrating the air conduit and an

outlet in section and showing the steam pipe and nozzle therein in side elevation;

Fig. 5 is a section view of a portion of the steam pipe and an outlet nozzle taken on line 5—5 of Fig. 1;

Fig. 6 is a longitudinal section of one of the conduits taken on line 6—6 of Fig. 1 showing the manner in which the steam pipe is centered and secured therein;

Fig. 7 is a section showing a modified form of my device attached to a furnace of the chain type;

Fig. 8 is a fragmentary view of a furnace showing the modified form of my device in side elevation in relation therewith;

Fig. 9 is a section taken on line 9—9 of Fig. 7 showing an air booster; and

Fig. 10 is a section of the same taken on line 10—10 of Fig. 9.

Referring now to the drawings by characters of reference Figs. 1 to 6 inclusive illustrate my invention used in connection with a horizontal return tubular boiler type of furnace wherein 21 represents the side walls, and 22 the end walls thereof. The firebox is located above the grate 23, and the space below the grate is referred to as the ash pit. This furnace is of a conventional design and is merely representative, as my device can be adapted for use with various other types of furnaces.

Conduits 25 extend longitudinally within recesses provided in the side walls of the furnace. The inner ends of the conduits, or headers, are threaded and receive apertured caps 26, these ends of the conduits extending into pockets 27 in one of the end walls of the furnace. The opposite ends of the conduits extend through apertures 28 in the opposite end walls, and suitable refractory material 29 encloses the spaces therebetween. Apertured caps 30 are threaded upon the ends of the conduits which protrude through the end wall, to secure them in position with the furnace walls, and to act as closures for the same.

A plurality of spaced outlets 31 extend from the conduits toward the firebox, and their open ends lie preferably flush with the inner portion of the side walls. These outlets in one conduit are located intermediate the outlets in the conduit at the opposite side wall of the furnace, and other than this difference, my device at one side of the furnace is the same as that at the other side.

of the furnace. The outlets are designed to direct an oxygen containing gas downwardly toward the opposite side of the firebox.

5 A plurality of spaced air inlets 32 extend downwardly from the conduits, within the recesses in the side walls, and curve inwardly under the grate 23 into open communication with the ash pit. These inlets are 10 preferably arranged, so that an inlet is positioned adjacent each outlet extending from the conduits.

The conduits, the outlets, and the inlets are designed to feed the warm air from the 15 ash pit into the firebox above the grate, and are preferably made of tubing which is treated to withstand heat. A suitable refractory material 24 is used to fill in the recesses and the pockets within which the 20 tubes are positioned, thereby protecting the tubes from the intense heat and securing them in position with the furnace.

Steam tubes extend longitudinally one 25 within each conduit and are provided with outlet nozzles which are located to align with the outlets in the conduits. The steam tubes may be made up of sections of pipes 33, which are connected at their ends by intermediate unions 34 into which the threaded 30 nozzles 35 are secured. The ends 36 of the inner sections of the steam tubes are closed and cone shaped. The steam pipes project into and are secured within the conduits and are arranged to be removed therefrom, when desired, without interfering 35 with the operation of the furnace. To assemble the steam pipes within the conduits the caps 30 are removed and the cone shaped ends 36 are inserted within the apertures, 40 in the caps 26. The pipes are then rotated until the outlet nozzles extend in the outlets of the conduit, whereupon the nuts 37 are placed in proper relation upon the threaded sections of the pipes 38 to act as 45 stops for the caps 30. The caps 30 are then screwed upon the steam pipes until they engage the furnace wall, after the cone shaped ends of the pipes have been firmly seated against the apertures in the caps 26. 50 Nuts 39 are then screwed upon the steam pipes until they engage the caps 30. A suitable union 40 is secured to the protruding end of each steam pipe, and supply pipes 41 engage and communicate therewith. 55 Valves 42, which can be operated automatically, or manually, regulate the pressure and volume of steam which passes into the pipes 33.

My device is adapted for use especially 60 when there is a green fire, when draught in the furnace is being forced, or at such other times during which the condition of the fire is such that light volatile fuel or gases become separated from the bed of fire and 65 are liable to be carried up with the air

draught. It will be seen that when in operation, the steam passing through the conduit outlets will draw air through the inlets, into the conduits, and out into the firebox through the outlets. When the air reaches a point in the outlets beyond the steam nozzles, it will be projected toward the opposite side of the firebox in a downward direction, and I prefer to provide steam under sufficient pressure such that the air will be forced into the firebox with sufficient force to provide an air blanket. With the outlets arranged as described, the fire is entirely covered by the air blanket, which blanket extends downwardly from opposite sides of the firebox to keep the combustible fuel in close proximity to the fire. In this manner such fuel, which ordinarily passes through the chimney with the draught, is retained in close proximity over the fire until completely burned, thereby abating the smoke and utilizing all of the combustible fuel. Fresh air which is heated contains a high percentage of oxygen, and I find that it assists the combustion of the fuel which lies between the fuel bed and the air blanket, and I therefore lead air into the conduits from the ash pit.

In Figs. 7 to 10 inclusive, I have illustrated a modified form of my device used in conjunction with a furnace of a different type. The general spring of the invention is applied here, as previously described, with the device located substantially outside of the furnace, eliminating the provision of housing recesses in the side walls and it is secured with the furnace, so that it may be entirely removed therefrom without interfering with the operation thereof. The device as shown in this instance is applied to only one of the side walls of the furnace, and it is to be understood that a similar arrangement is provided at the other side of the furnace.

In this instance 50 illustrates a longitudinally extending air conduit, or header, which is positioned externally of the side wall of the furnace, and which is provided with a plurality of spaced outlets 51. The outlets extend into openings through the side wall of the furnace and are in open communication with the firebox, and refractory material is provided within the openings and the outlets. The outlets are also arranged to direct air in a downward direction into the firebox, for the purpose heretofore described. A single air inlet 52 extends centrally from the conduit and opens into the ash pit below the grate 23, but if desired a plurality of such inlets, leading to the conduit, could be used.

A steam pipe 53 extends through a portion of the lower end of the inlet pipe and terminates in a nozzle 54 which opens toward the air inlet, adjacent its end. The 130

nozzle is a hollow cross-shaped structure which is perforated centrally at its outer side to receive the steam pipe, which side is also perforated adjacent the steam inlet 5 to direct the steam back into the conduit inlet, thereby drawing air from the ash pit into the air inlet with the steam. This arrangement is designed as a booster to increase the volume and velocity of the air 10 drawn through the conduit. Such a booster is necessary only under certain conditions, and ordinarily the device operates efficiently without such assistance.

A steam pipe 55 lies within the conduit 15 and is provided with outlet nozzles, in a similar manner and for the same purpose as previously described in my preferred embodiment. Suitable valves 56 and 57 are provided in the steam pipes 55 and 53 respectively, to regulate the flow of the steam 20 into the outlets as desired. A butterfly or similar valve 58 is provided within the air inlet pipe to regulate the volume of air desired, or to close the same if desired, and 25 this valve can be operated by hand or by mechanical means.

Various changes can be made in the details of the described mechanism without

departing from the spirit of my invention and the scope of the appended claim. 30

Having described my invention, what I claim is:—

The combination with a furnace, of a device for abating smoke and promoting combustion of the fuel comprising air conduit 35 pipes, outlet ports leading from said conduits into opposite sides of the furnace firebox, inlet ports leading from the space beneath the furnace grate into said conduits, steam pipes having outlet ports coaxial with 40 the outlet ports of said conduits for ejecting air therethrough from beneath the furnace grate, steam pipes extending partially through the inlet ports and projecting from the ends thereof within the space beneath 45 the furnace grates, box shaped nozzles secured to the ends of the steam pipes in said inlet ports, said nozzles having apertures therein for directing air into said inlet ports from said furnace, and means for controlling the volume of mixture of air and 50 steam passing into said conduits.

In witness whereof, I have hereunto signed my name this 5th day of May, 1923.

PETER J. SHOMER.
